UNITED STATES PATENT OFFICE.

KARL EGGART, OF ARBON, SWITZERLAND, ASSIGNOR TO THE FIRMA ADOLPH SAURER, OF ARBON, SWITZERLAND.

EMBROIDERING-MACHINE.

1,207,727.

Specification of Letters Patent. Patented Dec. 12, 1916.

Application filed February 3, 1914. Serial No. 816,146.

To all whom it may concern:

Be it known that I, KARL EGGART, a subject of the Emperor of Germany, residing in Arbon, Switzerland, have invented certain new and useful Improvements in Embroidering-Machines, of which the following is a specification, reference being had to the accompanying drawing, which forms a part hereof.

10 This invention relates to the suspension of the work frames of embroidering machines and has been developed with particular reference to its application to Jacquard embroidering machines, although its use is not necessarily limited thereto. Work frames of embroidering machines have been suspended heretofore upon interconnected levers, but in such cases the levers remote from the jacquard end of the machine have been connected to the lever which is directly acted upon by the jacquard or automat by a single tension member or at least by a tension member which acts only in one direction, namely against the weight of the work frame, the 15 various parts which have been moved upwardly through the pull of the tension member moving in the opposite direction under the influence only of the weight of the work frame. It has been found, however, that 20 when embroidering machines provided with such frame suspension are operated at high speed there is more or less lack of absolute uniformity in the movements of the several suspension levers and that the movement of 25 the frame and therefore the quality of the work produced are unfavorably influenced thereby. In accordance with the present invention provision is made whereby movement of the levers directly actuated by the 30 jacquard or automat in both directions, up and down, is imparted through tension members to all of the suspension levers, so that all of such levers and therefore all parts of the work frame are moved positively in both 35 directions, even at high speeds, and greater uniformity in the quality of the work is attained.

The invention will be more fully explained hereinafter with reference to the accompanying drawing in which a convenient embodiment of the invention is illustrated by way of example and in which the single figure is a view in front elevation of the frame of an embroidering machine with its

work frame, suspension levers and connections to the jacquard or automat.

The jacquard or automat, indicated generally at 1, is shown as having a shaft 2 provided with a bevel gear 3 which meshes with a bevel pinion 5 on a vertical screw shaft 4 supported at its upper end in a bracket 9. On the screw shaft is a traveling sleeve or nut 6 which engages a rod 7 pivotally connected at its upper end to a suspension lever 10 which is pivotally mounted at 11 on the machine frame 8, and to the horizontal arm of a three-armed lever 12 which is pivotally mounted at 13 on the machine frame 8. The upper arm of the three-armed lever 12 is connected by a tension member 14 with the bell crank suspension levers 15 (one or more) suitably distributed and supported upon the machine frame. The lower arm of the three-armed lever 12 is connected by a tension member 16 with the vertical arm of a bell crank lever 17 which is pivotally mounted on the machine frame, the horizontal arm of the lever 17 being connected by a tension member 18 with the horizontal arm of one of the suspension levers 15. The tension members 14 and 16 may be supported at intermediate points, as at 19, 20 and 21, to prevent sagging.

In the construction shown the weight of the work frame is counter-balanced by a counter-balance weight 22 which may be hung upon the lever 10 and through which the levers 10 and 12 may also be connected, as shown in the drawing.

The jacquard or automat moves the levers 10 and 12, to which it is directly connected in the manner shown, or in any other suitable manner, the lever 12 being provided as a matter of mechanical convenience. Movement of the levers 10 and 12 in a direction to raise the work frame 23 is imparted through the lever 12 and the tension member 14 to the suspension levers 15, while movement of the levers 10 and 12 in a direction to lower the work frame 23 is imparted to the suspension levers 15 through the lever 12, the tension member 16, the lever 17 and the tension member 18, the several suspension levers 15 being connected by the tension member 14 to move together whether the origin of motion is at one end of the series or at the other end. It will therefore be seen that the actuation of the jacquard or

automat in either direction, up or down, is imparted directly and positively to all of the suspension levers of the work frame so that all of such suspension levers and therefore all parts of the frame have precisely the same movement and the quality of the work produced will be the same throughout the length of the work frame.

It will be obvious that the counter-balancing of the work frame may be effected otherwise than as shown in the drawing, and in Letters Patent of the United States No. 1,123,504, dated January 5, 1915, there is shown and described a similar connection of the suspension levers through tension members acting in both directions in which the frame is counter-balanced by a spring. It will also be understood that the suspension levers and the actuating lever or levers may be arranged otherwise than as shown.

I claim as my invention:

1. In an embroidering machine, the combination of a machine frame, a work frame, suspension levers mounted on the machine frame and directly supporting the working frame, a multiple armed actuating lever mounted on the machine frame, and tension members directly connecting the arms of the actuating lever to the suspension levers for movement in both directions.

2. In an embroidering machine, the com-

bination of a machine frame, a work frame, a bell crank suspension lever mounted on the machine frame, a bell crank transmitting lever also mounted on the machine frame, a connection between one arm of the transmitting lever and one arm of the suspension lever, a multiple armed actuating lever mounted on the machine frame, a tension member connecting one arm of the actuating lever with another arm of said suspension lever, and a tension member connecting the other arm of the actuating lever with the other arm of the transmitting lever.

3. In an embroidering machine, the combination of a machine frame, a work frame, suspension levers mounted on the machine frame, a multiple armed actuating lever mounted on the machine frame, tension members connecting the arms of the actuating lever with the suspension levers for movement in both directions, and an automat directly connected to the actuating lever.

This specification signed and witnessed this 15th day of January, A. D. 1914.

KARL EGGART.
